UNITED STATES PATENT OFFICE.

HENRY F. HOFFMAN, OF NEW YORK, N. Y.

PIPE AND NUT WRENCH.

1,278,653.

Specification of Letters Patent. Patented Sept. 10, 1918.

Application filed November 11, 1916. Serial No. 130,737.

To all whom it may concern:

Be it known that I, HENRY F. HOFFMAN, a citizen of the United States, and a resident of the city of New York, Stapleton, borough 5 of Richmond, in the county of Richmond and State of New York, have invented a new and Improved Pipe and Nut Wrench, of which the following is a full, clear, and exact description.

10 This invention relates to quick adjustment of pipe or nut wrenches of the type covered especially by Letters Patent of the United States, No. 1,070,343, issued to me on August 12, 1913, which patent fully describes the 15 automatic action of the invention with respect to the adjustment of the movable jaw.

Among the objects of this present improvement is to provide a new specific form of locking dog for the adjustable jaw.

20 Another object of the invention is to simplify the construction and increase the strength and reliability of the pivoted yoke or that portion which carries the dog.

With the foregoing and other objects in 25 view the invention consists in the arrangement and combination of parts hereinafter described and claimed, and while the invention is not restricted to the exact details of construction disclosed or suggested herein, 30 still for the purpose of illustrating a practical embodiment thereof reference is had to the accompanying drawings, in which like reference characters designate the same parts in the several views, and in which

35 Figure 1 is a side elevation of the handle and jaw portions of the wrench with the yoke in vertical section, the wrench being shown adjusted for operation on a pipe;

Fig. 2 is a diagrammatic view of the 40 yoke and dog showing the manner of detachment of the dog from the yoke;

Fig. 3 is a horizontal section on the line 3—3 of Fig. 1, but omitting the jaw portions of the wrench;

45 Fig. 4 is a perspective detail view of the yoke separated from the other parts; and

Fig. 5 is a similar view of the dog detached.

Referring now more particularly to the 50 drawings, I show a nut and pipe wrench comprising relatively stationary and movable jaws 10 and 11 respectively. As in the previous patent mentioned, the stationary jaw is provided with a handle or shank 12 of any suitable construction or length, and the movable jaw is provided with a shank 13 disposed above and approximately par-

allel to the shank 12. The inner end of the shank 13 is provided with a pivoted member 14 constituting a combined finger piece 60 and lock for controlling the movements of the jaw 11 both longitudinally and angularly with respect to the stationary jaw, as fully set forth in my previous patent.

The yoke shown as a whole at 15 is made 65 preferably of a single piece of tubular material and consists of side plates 16, a top plate 17 and a connecting bar 18 at the bottom. These parts are all integrally connected, the side plates being parallel to each 70 other as are also the top and bottom members. This yoke may be made as a drop forging, as a casting or in any other convenient manner. The space between the top and bottom plates 17 and 18 is sufficient to 75 accommodate the shanks 12 and 13 therein and affords sufficient clearance for a limited amount of pivotal movement of the yoke around the axis of a main pivot pin 19 passing transversely through holes 20 formed in 80 the side plates 16 and the lug or hub 21 just within the stationary head 10. The head is formed with concave shoulders 22 concentric with the axis of the pin 19, whereby the similarly formed lugs or projections 23 of 85 the side plates are directly supported against the stationary head and whereby the main strain upon the wrench is borne by the stationary head rather than by the pin 19.

A light leaf spring 24 secured to the shank 90 12 acts normally upwardly against a pin 25 extending laterally through the holes 26 of the yoke between the shanks 12 and 13, the tendency of which is to cause the yoke to swing in a contra-clockwise direction around 95 the pivot 19, as viewed in Fig. 1.

The dog above referred to is indicated as a whole at 27 and comprises a substantially 100 rectangular body 28 having flat parallel sides having snug fit against the inner surfaces of the side walls 16 of the yoke. The plate 17 at the top of the yoke is preferably rounded or semi-cylindrical at its inner edge, as indicated at 17^a, while the outer edge of the same is less rounded. In other 105 words, the preferred form is that indicated in Fig. 2, in which said outer edge is approximately square, but rounded on the side adjacent to the dog at 17^b. The points 29 of the side plates 16 of the yoke project 110 slightly beyond the outer edge of the plate 17 and curve neatly and gracefully around to the outer surface of said plate. The outer end 30 of the dog conforms to the ends 29

of the yoke and fills the space between them. At the inner end of the body 28, the dog is provided with an outwardly projecting hook 31 which embraces or fits snugly around the 5 semi-cylindrical edge 17^a. The edge 17^a constitutes a fulcrum or pivot around which the dog is adapted to be turned in assembling the device or removing the dog from the yoke, Fig. 2 indicating the action of the 10 dog when it is being removed. In other words, by tapping the outer end 30 of the dog, said end may be forced downwardly or away from the plate 17, the dog swinging around the axis of the edge 17^a, so that 15 when the point of the end 30 comes below the plate 17, the dog may then be forced directly out from between the side plates 16 and the same or another dog may be put in its place by reversal of these movements. 20 A tail piece 32 extends inwardly from the hook 31 in a general direction parallel to the shanks of the wrench, and if desired the dog may be provided on opposite sides of the tail piece with shoulders 33 which are adapted to abut squarely against the inclined edges 16' of the side plates in normal condition of the wrench. The dog is provided with a series of teeth 34 which coöperate directly with similar teeth 35 formed on the 25 movable jaw shank 13 and whereby the movable jaw is held from outward movement when in use or when set for use by the locking device 14. By depressing the tail piece 32 toward the shank 12, the yoke is swung 30 in a clockwise direction around its pivot 19 causing the teeth 34 to disengage the teeth 35. In this position the movable jaw is free to slide freely outwardly as far as desired or until it is stopped by a pivot screw 36 35 projecting through the inner end of the shank 13 and adapted to abut against the edge 16' just described. In order to remove the movable jaw, the screw is taken out setting the shank 13 free for endwise movement and then the dog may be easily removed as before described and another put in its place. While, however, the shank 13 remains in its place between the plates 16 of the yoke, it is impossible for the dog to be 40 come displaced or loose for the reason that the point 30 can by no possibility drop sufficiently far toward the stationary jaw to pass the plate 17 and inasmuch as the hook 31 always embraces the round edge 17^a of 45 said plate, force applied upon the tail piece cannot permit the movement of the dog independently of the yoke itself. In other words, the hook and rounded edge 17^a constitute a fixed connection for the dog for all 50 practical purposes whether the shoulders 33 be used or not, but I prefer to use the shoulders because a more satisfactory connection is made thereby with the yoke. I wish to

emphasize particularly several advantages for this improved structure. First, the yoke being made in one piece including the plate 65 17 is exceedingly simple and easy to make and possesses the maximum strength. Again, the dog being made separate and separable from the yoke is preferably of a 70 superior quality of steel with the teeth thereof hardened and if the same should become damaged or worn, a new dog may be put in its place at slight cost as to time and money. 75

I claim:

1. As a distinct article of manufacture, the herein described locking dog for wrenches consisting of a unitary solid block of metal comprising a body portion having opposite flat parallel sides, a series of teeth 80 formed on one face of the body and extending from one side to the other, there being provided a pair of outward projections on the face opposite the toothed face, one of said projections being undercut, laterally 85 projecting shoulders formed at the ends of said flat sides, and a tail piece extending from the end of the body having the undercut projection and between the shoulders, 90 substantially as set forth. 90

2. The combination with a stationary member, a member movable with respect thereto and a yoke pivoted to said stationary member and loosely embracing the movable member, said yoke comprising a flat plate and side plates integral therewith, said plate having a semi-cylindrical inner edge extending between the side plates, and a detachable locking dog fitted between said side plates and having extensions engageable 100 with the inner and outer edges of said plate, one of said extensions being undercut to engage over and interlock with said inner edges forming a pivot bearing around which the dog is tiltable, and a tail piece extending 105 inwardly from the latter mentioned extension, the tail piece being so disposed that pressure thereon serves to maintain the other extension in engagement with the outer plate edge. 110

3. In a quick-adjustment wrench of the character set forth, the combination with relatively stationary and movable members and a unitary loop-shaped yoke surrounding said members and pivoted to one of them, 115 said yoke having a pair of parallel side plates with inclined inner edges, of a detachable locking dog fitted between said side plates and having interlocking engagement therewith, said dog having laterally projecting shoulders fitted normally squarely against said inclined edges, said dog also being provided with an inwardly projecting rigid tail piece, pressure upon which is resisted by said shoulders. 120

HENRY F. HOFFMAN.
